HOUSING FOR ELECTRICAL CONNECTORS

Lester E. Wilson, 1 Short St., Bedford, Mass. 01730,
and Stephen Anthony Machcinski III, 19 Seymour St.,
Winthrop, Mass. 02152

Filed Feb. 12, 1975, Ser. No. 549,451

Term of patent 14 years

Int. Cl. D13—03

U.S. Cl. D26—1 A

Fig. 1.

Fig. 2.

Fig. 3.

Fig. 5.

Fig. 4.

FIG. 1 is a view in perspective showing a housing for electrical connectors showing our new design;

FIG. 2 is a top plan view thereof, the bottom view being identical;

FIG. 3 is a view in side elevation of the housing;

FIG. 4 is a front view of the housing; and,

FIG. 5 is a rear view of the housing.

We claim:

The ornamental design for a housing for electrical connectors, as shown and described.
